UNITED STATES PATENT OFFICE.

FRANCIS THOMAS MURRAY, OF SOROTI, UGANDA, AFRICA.

GUTTER AND ROOF SURFACE.

Application filed August 6, 1925. Serial No. 48,677.

This invention consists in improvements in or relating to gutters and roof surfaces and has for its object to provide an improved arrangement of the gutter in relation to the roof surface. The improvements are particularly applicable to corrugated iron roofs although they are not limited to such roofs.

The present invention comprises the combination with a roof surface of a gutter so positioned on that surface that it is set above the lower edges or eaves of the roof with one edge or lip of the gutter lying in contact with or formed as part of the roof surface. Conveniently the fall of the gutter is obtained by arranging the latter so that it slopes downwardly towards its outlet across the upper surface of the roof.

When the roof is formed of corrugated material that portion of the gutter wall which is held in contact with the surface of the roof is, according to another feature of the invention, correspondingly corrugated to ensure a close fit between the gutter and the surface of the roof.

The invention also includes a roof-gutter so formed that it can be affixed to the surface of the roof above the lower edge thereof with one edge of the gutter in sufficiently close engagement along its length with the roof to deflect the water flowing down the roof into the gutter channel.

In order that the invention may be more clearly understood one preferred form of it will now be described in detail with the aid of the accompanying drawings in which:—

Figure 1 is a section through a gutter according to the invention and that part of the roof and wall (of the building to which it is attached) adjacent to it;

Figure 2 is a fragmentary perspective view showing the invention at the angle of the roof;

Figure 3 illustrates in perspective a portion of the guttering and the down-flow pipe leading therefrom at an angle of the gutter; and

Figure 4 is a perspective view showing a building with gutter attached to illustrate the fall of the gutter.

Like reference numerals indicate like parts in the several figures of the drawings.

In the construction illustrated the roof is assumed to be formed of or covered with corrugated iron or like corrugated material 10. As shown clearly in Figures 2 and 3

that edge of the gutter 11 which is to be applied to the roof is also formed with corresponding corrugations either formed before the gutter is applied to the roof or subsequently to its application thereto. In the latter case the gutter will conveniently be formed of malleable galvanized iron or other malleable metal which can be hammered to fit into the corrugations.

The gutter is conveniently secured in place by means of nails or the like 12, Figures 1 and 2, which take into roof purlins 13. The invention, however, is not limited to this particular method of securing the gutter in place. Alternatively the edge of the roof may be turned up to form a gutter and false eaves can then be provided to extend beyond the gutter in which case the roof and gutter are in one piece. For instance, as seen in the drawings the gutter and that part of the roof 10 extending from it towards the ridge of the roof may be in one piece and the extension of the roof beneath the gutter and beyond it towards the lower edge of the roof 80 may be separately applied to constitute false eaves.

In many tropical countries buildings are frequently provided with galvanized iron roofs such as that described above, which 85 may be corrugated or otherwise, and it is desirable to collect into tanks as much water as can possibly be obtained from the roof. Hitherto the gutter has generally been fixed to a board arranged below the eaves and 90 unless this board is very deep it is impossible to obtain sufficient fall for the gutter to deal with the water collected from tropical rains. When the fall is insufficient, only a portion of the roof can be adequately 95 drained; moreover it is necessary to have the gutter cleaned out periodically and in doing so a ladder is usually leaned against the edge of the gutter. As the material of the latter is generally of a somewhat flimsy 100 character it is often bent out of shape thus causing hollows or indentations to be made such that water can collect in the hollows or indentations. These collections of water are found to be highly objectionable in that mos- 105 quitoes, for example, breed in them.

With a gutter according to the present invention, however, any required fall can be obtained as the gutter, in the direction of its length, can be sloped to any desired 110 degree across the surface of the roof. This is shown clearly in Figure 4 where the gut-

ter slopes downwardly along the faces of the roof to a down-flow pipe 14 from which water passes into a collecting tank 15.

It will also be realized that a ladder used 5 for obtaining access to the gutter will rest against the edges or eaves of the roof where they project beyond the gutter and not against the latter which is set sufficiently far above the edge of the roof to avoid contact 10 between it and the ladder.

The down-flow pipe 14 can be passed into the gutter as shown in Figure 3 through an orifice therein and can then be flanged over at 16 and riveted in place to the gutter.

15 It is obvious that the invention is not limited in its application to iron roofs, corrugated or otherwise as it may be applied to any construction of roof where it is possible to fix the gutter so that one edge will 20 lie sufficiently closely to the roof to collect water flowing down the latter, or in which the gutter can be formed as a part of the roof material. In Figure 4 the roof is shown as a plain roof but it will be understood that this can represent a roof of any 25 material and of any preferred form.

In the case of a gabled roof as shown in Figure 4, formed with hipped ends, the gutter can, in passing round the roof, slope 30 downwardly and continuously (in both directions around the roof) as illustrated. The tank 15 may be of such a height as to

extend right up to or close under the eaves of the roof, thus enabling a greater height of tank to be employed for any given building than would be possible when the gutter 35 is fixed below the eaves.

I claim:—

1. A gutter for application to a sloping corrugated roof surface above the lower edge 40 thereof, said gutter having a body portion curved in cross section and constituting a trough, and a lateral attachment portion in the form of a corrugated lip shaped and extending at such an angle therefrom that it 45 can be laid snugly along the sloping corrugated roof surface substantially parallel with the lower edge thereof.

2. A gutter for application to a sloping corrugated roof surface above the lower 50 edge thereof, having a body portion curved in cross section and constituting a trough, and an integral lateral portion in the form of a lip, which lip is corrugated to correspond to the corrugations of the roof, and extends at such an angle from the body portion that it can be laid snugly along the sloping corrugated roof surface, and when so laid, the trough will extend substantially horizontally away from the roof surface 55 with the middle of the bottom of the trough spaced away from the roof.

In testimony whereof I affix my signature.

FRANCIS THOMAS MURRAY.
